UNITED STATES PATENT OFFICE.

EDWARD F. CALDWELL, OF NEW YORK, N. Y., ASSIGNOR TO THE PHOENIX
GLASS COMPANY, OF PITTSBURG, PENNSYLVANIA.

DESIGN FOR A GLOBE OR SHADE.

SPECIFICATION forming part of Design No. 26,640, dated February 16, 1897.

Application filed January 13, 1897. Serial No. 619,123. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

My invention has relation to designs for globes or shades for gas, lamp, or electric lights, and has for its object the provision of a novel design of pleasing appearance; and my invention consists in the ornamental configuration hereinafter described, and shown in the accompanying drawings, wherein—

Figure 1 is a plan view, and Figs. 2 and 3 are side views, of a globe embodying my design.

The body of the globe consists of a number

of flat panels A A A, joined edge to edge and curving outwardly toward the top, thus forming a bell-mouthed article polygonal in cross-section. The upper edge of each flat surface or panel is concaved, and the lower ends of the same are bounded by curved lines b b b, while the body of the globe merges into the neck of the same through a sharply-inturned curved portion B. Suitable surface ornamentalations, such as etched figures and the like, may be applied to produce additional ornamental effects.

Having described my invention, I claim—

The design herein described and shown in the accompanying drawings.

In testimony whereof I have affixed my signature in presence of two witnesses.

EDWD. F. CALDWELL.
